UNITED STATES PATENT OFFICE.

ALBERT WANNER, JR., OF HOBOKEN, NEW JERSEY.

DESIGN FOR A HINGE.

SPECIFICATION forming part of Design No. 25,508, dated May 19, 1896.

Application filed April 14, 1896. Serial No. 587,566. Term of patent 7 years.

To all whom it may concern:

Be it known that I, ALBERT WANNER, Jr., of Hoboken, in the county of Hudson and State of New Jersey, have invented and ⁵ pro-
duced a new and original Design for a Hinge, of which the following is a full, clear, and exact specification.

Reference is to be had to the accompanying drawing, forming a part of this specification, ¹⁰ in which the figure is a side edge view of a hinge embodying my new design.

The leading feature of my design consists in the hinge having ornamental work along a

face of the hinge and disposed at an angle thereto. ¹⁵

Another feature of the design is a depending elongated ornament adjacent to the meeting ends of the hinge members.

I claim—

The design for a hinge herein shown and ²⁰ described.

ALBERT WANNER, Jr.
